UNITED STATES PATENT OFFICE.

MOSES G. HUBBARD, OF NORRISTOWN, PENNSYLVANIA.

CAR-TRUCK.

SPECIFICATION forming part of Letters Patent No. 326,652, dated September 22, 1885.

Application filed September 5, 1884. (No model.)

To all whom it may concern:

Be it known that I, MOSES G. HUBBARD, of Norristown, county of Montgomery, and State of Pennsylvania, have invented a new and 5 useful Improvement in Car-Trucks, of which the following is a full, clear, and exact description, reference being had to the accompanying drawings, making part of this specification.

10 My invention relates to an improvement upon the car-truck described in my pending application, filed April 12, 1884, and more particularly to the suspending of the torsion rods or springs which uphold the bolster 15 upon pendent vibrating links arranged to resist and regulate the lateral play of the bolster, and to the construction of the bearings for the working ends of the torsion rods or springs, whereby the latter are adapted to roll 20 in said bearings, thereby obviating the frictional resistance consequent upon a sliding movement of the rod or spring, and making the latter more delicate in action and more durable than when the spring is made to slide 25 in its bearings.

It further relates to the combination of the torsion rods or springs which support the bolster with bars secured to the lower face of the bolster, and arranged, in combination with 30 transverse bars of the truck-frame, to limit the upward movement of the bolster; also, to the combination, with the bolster and transverse truck-frame bars, of suitable bars or pieces connected with the upper side of the bolster 35 for limiting its downward movement in such manner as to leave sufficient vertical play of the bolster to accommodate the proper working of the supporting-springs.

It further relates to the arrangement of the 40 swinging bolster and its attachments relative- ly to the supporting cross bars or sills of the truck - frame, whereby said cross - sills are adapted to hold the bolster safely in position should any of the supports of the latter break 45 or become detached, and at the same time to leave the bolster free to move independently of the sills while in operation.

It further relates to the manner of combin- 50 ing the long recurved torsion rods or springs supporting the bolster with the truck-frame by means of pendent links adapted to allow the bolster to swing freely in every direction,

except as its movements are limited by de- vices hereinafter described.

It further relates to the combination, with the bolster, its springs, and outwardly-inclined sustaining-links, of draft links or rods pivoted to the truck-frame and bolster, and serving to limit the backward and forward movement of the bolster and of the car-body connected therewith, to remove the draft of the truck from the vertical supports of the bolster and its springs, and to assist the outwardly-inclined links which uphold the bolster and its springs in controlling the lateral movement of the bolster.

It further relates to the construction of the truck-frame and to the combination of the journal-boxes for the axles directly, with the ends of the longitudinal sills projecting beyond the cross sills or bars, all of the latter being arranged between the axles, thereby forming a short and compact truck-frame, all as hereinafter described; and it further re- lates to the manner of suspending the brake-bars from the truck-frame, and to the com- bination, with the latter, of pendent loop- brackets which permit the required move- ment of the brake - bars, giving increased steadiness thereto, and serving as a safety attachment to said bars in case of accident to their other supports.

I have found that in the ordinary construc- tion and arrangement of these parts the entire friction caused by the whole draft of the train intervenes between the wheels and the cars to prevent the free vertical and lateral vi- bration of the wheels and cause them to com- municate a large portion of the force of their jar or vibration to the cars, the same as if connected by rigid supports, and however delicate the springs might be, their vibrations would in a great measure be destroyed by this friction, which must first be overcome before they would act. The aggregate of friction amounts (to the full extent of its vertical force) to per- fectly rigid and solid supports and connections between the wheels and the cars, and is the first cause of the great vibration and noise communicated to the cars by the wheels in all of the ordinary forms of car-trucks. When this, to a great extent, solid support or con- nection between the car-body and wheels is remedied by the practically frictionless

raft-links or their equivalent, and the car-
ried on my long circumferential springs,
early all communication of vibration and
noise from the wheels to the car is removed.
In the accompanying drawings, Figure 1 is
bottom view of a car-truck with my improve-
ments applied; Fig. 2, a side elevation of the
same; Fig. 3, a vertical longitudinal section
at the line $\alpha\alpha$; Fig. 1, and Fig. 4 a side elevation
of one of the torsion-spring journal-
boxes detached, with the spring in place
therein in section.

$\Delta\Delta'$ represent the side longitudinal sills
of the truck-frame, $B B' B^2 B^3$ the transverse
sills, and C and C' the axles mounted directly
in bearings in the ends of the side sills, A and
 A' , projecting beyond the outer cross-sills or
bars, B^2 and B^3 , as shown.

D is the bolster, arranged between the in-
termediate cross bars or sills, B and B' , a the
fit-wheel or central support on said bolster
on which the car-body rests, and $b b'$ bars or
pieces attached to the ends of the bolster, on
its upper side, with their ends overhanging
the cross-bars B and B' , said pieces serving to
steady the car-body and to limit the downward
movement of the bolster should any of its sup-
ports become broken or detached.

$E E'$ are longitudinal bars secured to the
ends of the bolster, on its lower face or side,
and which, underlying the transverse bars B
and B' , serve to limit the upward movement
of the bolster. The long U-shaped or recurved
torsion rods or springs F , described in my
former application referred to, are secured to
these bars E and E' , and the free or crank ends
hereof are secured in bearings f thereon,
which are slightly elongated to permit the
rods to roll in the bearing, thereby avoiding,
within certain limits, the friction resulting
from the revolving of a round journal in a
cylindrical bearing, and rendering the spring
more sensitive than where the ordinary cylin-
drical bearing is employed. Beyond the limit
provided for the elongation of the bearings
or the rolling of the rods the latter can ro-
tate in the bearings in the usual manner, there-
by bringing into action the frictional resist-
ance referred to, to prevent excessive move-
ment of a torsional strain upon the rods or
springs.

$d d d d$ are the links by means of which the
springs are suspended, said links being con-
nected at their upper ends, by suitable eyes or
bearings, with the transverse bars B and B' , or
other suitable points on the truck-frame, and
incline outward laterally to their lower ends,
where they are connected by suitable eyes or
bearings with the ends of the cranks on the
torsion rods or springs, as shown.

It requires but a slight elongation of the
journal-boxes f to permit all of the rolling
movement required for the ordinary vertical
vibrations of the car-wheels, and then the jour-
nal portion of the spring comes in contact with
the circular end of the box during the balance
of its movement, and acts in it precisely as if

the journal-box were round, because the ten-
dency is to roll up against the end of the box.
This journal-box should be so proportioned
that the spring will roll up against the end
of the box immediately upon finishing its or-
dinary vibratory movement, which is but
slight, and yet necessary in order to give to
the very large spring and very short crank-
arms, necessary for carrying a railway-car
body, the easy and free vibration required.
The eye or bearing at the lower end of each
link should have a similar elongation to allow
the crank-pin or eye on the end of the spring
crank-arm to roll in the link-bearing in a man-
ner similar to the spring in, the elongated
journal-box, and this is one reason why it is
best to hang the springs on long free links.

By inclining these spring-links outward at
their lower ends I accomplish all of the ob-
jects of such inclination described in my said
pending application, and at the same time
utilize the links for both purposes of spring-
links and outwardly-inclined bolster-links.
These links give to the bolster the desired lat-
eral freedom, and by their inclination may pos-
sibly secure sufficient lateral steadiness to the
car, and undoubtedly would if the draft-links
are used as described and shown, as they
would co-operate with the outwardly-inclined
links in controlling the lateral movement of
the bolster. These draft-links are shown at
 g and g' , and may be attached at other con-
venient parts of the truck to serve the pur-
pose. They should be arranged to draw from
either direction, because the car is designed
to be drawn in either direction. Such a friction-
less draft might be arranged both to pull
or to push, or links might be made in pairs
and attached out near the ends of the bolster,
or mechanical equivalents for them, which will
break or obviate the great frictional adhesion
of the supports between the wheels and car
caused by the draft of the train, and which it
is necessary to overcome before any spring
can act to remove or effectually diminish the
jar and vibration of the wheels upon the car.
The eyes or perforations in these draft links
or rods are elongated to permit the vertical
vibration of the ends connected with the bol-
ster; or other suitable provision may be made
for that purpose, care being taken, however,
to prevent undue backward and forward vi-
bration of the bolster.

The brake-bars (indicated at $H H'$) are sus-
pended from the longitudinal sills A and A'
by pendent pivoted links h and h' at each end,
said bars being arranged between the wheels
and in suitable relation thereto to adapt the
brakes H^2 to be readily brought to bear upon
the wheels, the ends of the brake-bars resting
in suitable pendent loop-brackets, I , secured
to the lower face or side of the sills A and A' ,
as shown. These loops serve to guide and
steady the movements of the brake-bars, and
form also safety attachments therefor in case the
suspending-links or other attachments become
detached or broken. The sustaining-links h

h' are pivoted, by preference, to the outer sides of the sills A and A', and to the ends of the brake-bars outside of the pendent brackets H, as shown, leaving the space outside of and between said sills and between the axles free and unobstructed for the operative movements of the bolster and its attachments and of the brake-actuating mechanism.

In a truck having equalizing-bars, as in ordinary car-trucks, or such as shown in my pending application above referred to, the equalizing-bars may be attached to the journal-boxes, in which case the draft-links may be pivoted to the equalizing-bars and to the truck-brackets.

When the brakes are applied to the wheels to stop the train, the greatly-increased resistance of the wheels and the great increase of draft upon them, caused by the momentum of the train, proportionally increases the pressure between the ordinary vertical supports of the car and the resulting friction between the surfaces. The momentum of the car being often several times its own weight, it is obvious that operating against the great resistance of the wheels when the brakes are applied, a pressure and friction between the car-supports is often caused sufficient to prevent the action of the car-springs and give the car nearly all of the jar of the wheels. This is especially annoying in sleeping-cars, and very disagreeable in all passenger-cars. An anti-friction draft-connection of the car to the wheels, as above described, remedies this effect of the draft upon the springs by permitting their free action as perfectly when the brakes are applied to stop or overcome the momentum of the car as when it is being drawn forward by the locomotive.

Having now described my invention, I claim as new—

1. In a railroad-car truck, the long recurved springs and the short crank-arms, in combination with the pendent links connected with said crank-arms, substantially as described.

2. In a railroad-car truck, the long recurved springs and short crank-arms, in combination with the pendent links inclined outward toward their lower ends and secured at said ends to said crank-arms, substantially as described.

3. In a car-truck, the long recurved springs provided with short crank-arms, in combination with the pendent links supporting said crank-arms and springs, and with journal-boxes having slightly-elongated bearings for said springs to roll in, substantially as described.

4. In a car-truck, the long recurved springs, in combination with and secured to the bolster, and the interposed bars arranged transversely of the bolster, and adapted to limit the upward movement thereof, substantially as described.

5. In a car-truck, a swinging bolster located between contiguous cross-sills, by which its movement is limited, in combination with the pivoted links or anti-friction draft attachment adapted to permit such limited movement of the bolster, and the springs upon which said bolster is mounted, substantially as described.

6. In a car-truck, the bolster suspended by swinging links in such manner as to be free in every direction, except as controlled by and in combination with the springs, spring-bars, steadyng-pieces, and draft-links, substantially as described.

7. A car-truck frame constructed as described, in combination with the bolster suspended therein by means of pendent links, and controlled in its position longitudinally of the truck by the anti-friction draft-links, substantially as specified.

8. The anti-friction draft-links interposed between the car and wheels, in combination with the springs upon which the car is mounted, substantially as and for the purposes specified.

9. The anti-friction draft-links, in combination with the laterally-vibrating bolster-links, for the purposes, and substantially as described.

10. In a car-track, the draft-links connecting the car-body with the truck or wheels, in combination with the springs interposed between said car-body and the truck, for the purposes described.

11. The combination, with the car-truck, of anti-friction draft-links arranged to draw said truck in either direction, substantially as described.

12. In a car-truck, the brakes and wheels attached to the truck-frame, in combination with and arranged to act upon the bolster only through the medium of the interposed springs and draft-links, substantially as described.

In testimony whereof I have hereunto set my hand this 3d day of September, A. D. 1884.

MOSES G. HUBBARD.
